CLAIM

The ornamental design for a sanding block, as shown and described.

DESCRIPTION

FIG. 1 is an exploded perspective view of a sanding block showing my new design;

FIG. 2 is a perspective view thereof;

FIG. 3 is a top plan view thereof, the bottom plan view being a mirror image;

FIG. 4 is a left side elevational view thereof, the right side elevational view being a mirror image;

FIG. 5 is a front elevational view thereof;

FIG. 6 is a rear elevational view thereof; and,

FIG. 7 is an enlarged perspective view of the wristband retention hook portion of the sanding block, shown separately for clarity of disclosure.

The dotted lines throughout the figures represent the distal end of the sanding block, and whose size and shape form no part of the claimed design.
